ARCHITECTURAL SIDING STRIP

Hugo E. Pannullo, 77 Atwells Ave., Johnston, R.I., and Hugh C. Neville, Barrington, and Hugh Neville, Jr., Tiverton, R.I., assignors, by direct and mesne assignments, of forty-two and one-half percent to said Pannullo, fifty percent to Anawan Plastics & Machine Corp., Fall River, Mass., a corporation of Massachusetts, and seven and one-half percent to Bernard Plante, Lincoln, R.I.

Filed May 11, 1964, Ser. No. 79,915

Term of patent 14 years

(Cl. D13—1)

FIG. 1 is a perspective view of an architectural siding strip showing our new design;

FIG. 2 is a rear elevational view thereof;

FIG. 3 is an enlarged end elevational view thereof looking at the left end of the strip shown in FIG. 1;

FIG. 4 is an enlarged section taken on line 4—4 of FIG. 1;

FIG. 5 is a top plan view thereof; and

FIG. 6 is a bottom view thereof.

The strip is shown broken in FIGS. 1, 2, 5 and 6 to illustrate indeterminate length.

We claim:

The ornamental design for an architectural siding strip, substantially as shown and described.
